AUTOMATIC SWITCH

Owen Avis Pearce and Reginald Taylor, Liverpool, England, assignors to Automatic Telephone & Electric Company Limited, Liverpool, England, a British Company

Application June 3, 1947, Serial No. 752,213
In Great Britain June 19, 1946

9 Claims. (Cl. 179—18)

1

The present invention relates to automatic switches of the type employed in telephone and like systems and is more particularly concerned with automatic switches which perform a group selecting function by testing for an idle outlet to succeeding equipment marked by the presence of a particular potential upon the test conductor.

In previous switches the possibility has existed that an outlet tests busy but, while the wipers are stepping from that outlet to the next but before the wipers are clear of the outlet, the outlet becomes idle, whereupon the switching relay may have time to operate to that idle condition and cause the switch to seize the succeeding outlet irrespective of its idle or busy condition.

It is the main object of the present invention to provide arrangements which will reduce this possibility and according to the invention the stepping of the wipers from one outlet to the next and the testing of the outlets is arranged to be effected sequentially without overlap. This ensures that no test circuit is available during the stepping of the switch and hence the possibility of the switching relay operating during stepping is substantially non-existent.

Preferably sequential stepping and testing is effected by employing changeover rotary magnet interrupter contacts and arranging the circuits so that the rotary magnet is operated over the back interrupter contacts while the test circuit is completed over the front contacts. The switching relay can thus only operate when the wipers have completed the step and the rotary interrupter contacts are operated and the desired sequence of step; test; step; test is obtained.

The invention is also concerned with arrangements for releasing the equipment which precedes the group selecting switch particularly when the switch is of the battery testing type. It is usual practise in circuit design to arrange for a brief unguard period to occur before the release of a switch in order to initiate the release of the preceding switches in the train. On earth-testing selectors it is easy to arrange for the unguard feature but on battery-testing selectors, which include a fast switching relay, the problem is more difficult. It is a further object of the present invention to avoid this difficulty and according to this feature of the invention, a slow and a fast relay are operated in series to control the connection to an idle outlet and on the release of the connection the circuit to said relays is opened, and earth potential is removed from the private wire on the release of the fast relay and replaced on the release of the slow relay to provide the

2

desired unguard period. The re-connection of guarding earth is effected on the release of the switching relay under the control of off-normal contacts. The initiation of the release may, of course, be due to the normal release of a connection or it may be due to a fuse blowing in a succeeding switch.

It is well known that there are at least two methods in general use for the testing of switch outlets. In one of these busy lines are marked by earth potential while in the second idle lines are marked by battery potential. A further object of the invention is to enable the group selecting switch to operate with preceding equipment employing either method and this is effected by means of a simple strapping between two tags, the existence of the strapping enabling the switch to operate with equipment of one type and the absence enabling it to operate with equipment of the other type.

The invention will be better understood from the following description taken in conjunction with Figs. 1 and 2 which show its application to a switch of the so-called rectangular movement type as described in United States Patent No. 2,028,689 issued January 21, 1936 to R. N. Saxby having two sets of wipers and adapted to test two groups of outlets simultaneously.

The condition of the P conductor when the switch is in the normal position is determined by the requirements of the preceding equipment. Where this is of the battery testing type leads 11 and 12 are strapped to connect battery via resistor YA to the P conductor, whereas if the preceding equipment is of the earth testing type this strap is omitted to open the P conductor.

When the switch is taken into use relay A is operated over the loop by way of its outer windings, and thereupon completes a circuit from earth at contacts N2 to operate relay B in series with resistor YC and vertical magnet VM. Relay B only operates over this circuit and at contacts B1 completes a locking circuit for itself, at contacts B3 earths the incoming P conductor to hold the preceding switches, at contacts B2 completes a circuit to operate relay HA from battery via resistor YB extended over contacts NR5, winding of HA to earth at contacts B3; at contacts B4 and B5 prepares testing circuits for relays HX and HY respectively, and at contacts B6 connects up the middle winding of relay A.

It may be mentioned here that the switch is equally suitable for use as a first group selector, an incoming selector or a subsequent group selector. If it is used as a first selector, the middle

winding relay A is, on the closure of contacts B6, connected by way of cam contacts S2 and common lead 13 to dial tone, and the relay in known manner serves as a tone transformer so that dial tone is audible to the calling subscriber. If the switch is used in positions other than the first selecting stage, dial tone is not connected to lead 13. Further, if the switch is used as a first selector, leads 10 and 11 may be strapped so that an immediate guard to the P conductor is provided by contacts A1 over contacts N3 and HA1 and test link TL2 in the manner described in United States Patent No. 2,424,519, issued July 22, 1947 to Reginald Taylor et al.

Relay HA upon operating, at contacts HA1 short circuits resistor YC to prepare for vertical stepping, at contacts HA2 and HA6 prepares for the disconnection of relay A, at contacts HA3 opens a point in the RM rotary magnet drive circuit and completes a circuit in series with the rotary magnet to the common conductor 16 to light the individual supervisory lamp LP. The common conductor 16 extends to exchange alarm equipment which provides a signal if the switch is seized but not operated within a predetermined time.

No further changes take place until a series of impulses forming a digit is transmitted to the switch, whereupon relay A responds accordingly, and on each de-energisation completes a circuit for magnet VM which now operates to raise the wipers a corresponding number of steps. Relay B is short circuited each time relay A releases and consequently remains operated during the impulse train. As soon as the switch moves off-normal the vertical off-normal contacts are operated and at contacts N1 a point is closed in the rotary magnet drive circuit; at contacts N2 the original operating earth for relay B is removed and relay B is now dependent on its own contacts B1. Contacts B1 also extend earth each time relay A operates, to short circuit relay HA which, however, is slow-to-release and remains operated. Finally at contacts N3 a point is opened in the immediate guard circuit, where this facility has been used, and prepares the release guard circuit.

At the end of the impulse train relay A remains steadily operated and relay HA is therefore short-circuited and releases, after a delay, to complete the rotary magnet circuit from earth on common lead 15. The magnet therefore operates to advance the switch wipers into engagement with the first set of bank contacts and, towards the end of the stroke, operates the interrupter contacts RMC which de-energise the magnet and complete P1 and P2 wiper testing circuits via the low resistance right-hand windings of relays HX and HY respectively. On the first rotary step the rotary off normal contacts NR operate and at contacts NR1 and NR4 make the subsequent disconnection of relay A dependent upon the operation of either the HA or HB switching relay; at contacts NR2 prevent false operation of the vertical magnet; at contacts NR3 ensures that resistor YC remains included in the vertical magnet circuit and at contacts NR5 connects the resistor YB across the rotary magnet.

Four possibilities now arise, viz. that wiper P1 will encounter an idle line and wiper P2 a busy line, that both wipers will encounter idle lines, that wiper P2 will encounter an idle line and wiper P1 a busy line, or that both wipers will encounter busy lines.

Consider the first case in which wiper P1 encounters an idle line while wiper P2 encounters a busy line. The idle condition of the OGA outlet P1 bank contact is indicated by a resistance battery on that contact whereas the busy condition of the OGB outlet P2 bank contact is denoted by an earth potential. At this instant the contacts RMC are operated and relays HX and HY simultaneously test the P1 and P2 bank contacts respectively, but relay HX alone operates from earth at common lead 15 extended by the operated RMC contacts via rectifier MRA, relay HX right hand low resistance winding to the battery potential on the P1 bank contact. Contacts HX1 opens a point in the rotary magnet circuit, to prevent further advancement of the wipers, and provide a circuit to energise relay HA and the left hand winding of relay HX in series with the rotary magnet, whereby relay HA is operated and relay HX is locked. Contacts HX2 apply an immediate guard to the P1 bank contact, to cover the operate time of relay HA, thereby seizing the free OGA outlet. Relay HA in operating, at contacts HA2 and HA4 connects the incoming (IC) negative and positive speech wires to the OGA outlet -1 and +1 wipers, disconnects relay A which releases and at contacts HA5 extends the P conductor to the P1 wiper. Relay A releasing, at contacts A1 short circuits relay B which then releases slowly to remove the local guarding earth from the P conductor at contacts B3 and B4. Relays HA and HX now remain operated from earth returned over the P wiper.

If both outlets OGA and OGB are idle, battery potentials are encountered by the P1 and P2 wipers, and the HX and HY relays consequently operated. Contacts HX1 prevent the operation of relay HB, and open a point in the rotary magnet circuit and cause relay HA to operate as in the case just described. The immediate guard applied at contacts HY2 to the P2 conductor is disconnected at contacts HA8 and relay HY is released at the same contacts. Relay HA in operating causes relays A and B to release in turn:

In the third case in which the OGA outlet is busy and the OGB outlet is idle, the P2 wiper encounters a battery potential and relay HY operates from earth at lead 15 extended by operated RMC contacts via rectifier MRB, relay HY low resistance right hand winding, contacts B5 and HA8 to the battery potential on wiper P2. Contacts HY1 open a point in the rotary magnet circuit and provide a circuit for energising relay HB and the left hand winding of relay HY in series with the rotary magnet whereby relay HB is operated and relay HY is locked. Contacts HY2 apply an immediate guard to the P2 wiper. The speech conductors are extended to the OGB outlet over operated contacts HB2 and HB6, relays A and B release, and the P conductor is extended to the P2 wiper over contacts HB1.

The purpose of the rectifiers MRA and MRB connected in circuit with the testing relays HX and HY is to prevent the operation of the relays on current reversal in case the wipers during rotary stepping encounter booster battery on an outlet in the metering condition as explained in United States Patent No. 2,137,422 issued November 22, 1938 to R. Taylor et al.

In the fourth case in which both P1 and P2 wipers encounter busy outlets, relays HX and HY remain in operative and consequently, when the interrupter contacts RMC restore to normal, the rotary magnet is re-energised and advances

the wipers a further step to the next set of bank contacts where all four possibilities are again operative. It may be pointed out the speed of rotary stepping is controlled by the value of the shunt resistor YB.

If the wipers are advanced over the whole group without either wiper encountering a free outlet, they attain the 11th step position at which relay HY operates, from battery at resistor YA extended over contacts HB5, P2, 11th step bank contacts, contacts HA8 and B5, right hand winding of relay HY, rectifier MRB and contacts RMC to earth at lead 15. Relay HY in operating disconnects the circuit to the rotary magnet and operates relay HB, whereupon the negative and positive conductors are connected to the -2 and +2 wipers but in this case relay A remains operated owing to the connection from the 11th contacts to the windings of relay A. Relay B is thus also held and relays HB and HY are locked to contact B3. At the 11th step position the cam operated springs S also operate and at S3 apply earth over the P1 wiper and lead 18 to operate the overflow meter (not shown). At contacts S1 alternate battery and earth is extended from common lead 14 to the left hand and middle windings of relay A, and at contacts S2 busy tone earth from common lead 17 is applied to the middle winding of relay A. This relay again acts as a tone transformer by repeating the busy tone to the calling subscriber, and it remains operated on the middle winding during the battery period on lead 14.

It may be pointed out at this stage that the circuit arrangement obtains immunity from switching to busy outlets by ensuring that the P1 and P2 testing circuits are applied whilst the interrupter contacts RMC are operated, and the rotary magnet RM is energised over contacts RMC normal, provided a test relay HX or HY is not operated, so that simultaneous closure of the stepping and testing circuits does not occur as in other known battery testing switches.

It may be further pointed out that the circuit arrangement also obtains immunity from multiple connections in the case of two or more selectors testing the same outlet simultaneously, by arranging that two or more testing relays, HX or HY, will not operate to a common battery potential on a P1 or P2 bank contact. The wipers of all switches concerned consequently continue to be advanced over the contacts until the faster switch is able to seize an outlet.

Upon the release of the connection at the end of the conversation, relays HA and HX or HB and HY, as the case may be, are disconnected when earth is removed from the P conductor. The test relay HX or HY releases quickly followed after a predetermined period by the slow release switching relay HA or HB. During the delayed release of relay HA or HB the incoming P conductor is maintained open to disconnect preceding equipment and after its release earth is re-applied by contacts HA7 or HB3 normal. Also when relay HA or HB releases the self-interrupted drive circuit to the rotary magnet is completed, from earth on lead 15 which extends to the alarm equipment, consequently the wipers are rotated clear of the banks and then returned to their home position where the off-normal contacts N restore. In restoring to normal contacts N3 remove earth from the P lead, and if the switch is preceded by other battery testing switches as evidenced by a strap connecting leads 11 and 12, apply battery via resistor YA to the P conductor.

If for any reason the switch fails to restore, the off-normal contacts N3 remain operated and as a result of the continuous connection of battery potential to lead 15, the release alarm indication is given after a predetermined period.

In the case of a fuse blowing when connection to the next selector is established, relays HA and HX or HB and HY release as explained after the release of the connection and again the P conductor holding earth is disconnected for the release time of relay HA or HB to release the preceding equipment.

When the calling party hangs up in response to the receipt of busy tone, relay A releases during one of the earth periods on lead 14, and thereupon short circuits relay B. This relay on releasing removes earth from the P conductor at contacts B3 and relays HA and HX or HB and HY are thereby released to function as in the case of release on termination of a conversation.

We claim:

1. In a telephone system, an automatic switch, a first circuit including a magnet for operating said switch, a second circuit including a relay for stopping said switch, contacts on said magnet for controlling said first circuit, other contacts on said magnet for controlling said second circuit, said contacts being arranged so that said first circuit is closed only when said second circuit is open and said second circuit is closed only when said first circuit is open.

2. In a telephone system, an automatic switch, incoming and outgoing conductors for said switch, a plurality of contacts accessible to said outgoing conductors, a magnet for operating said switch to thereby bring said outgoing conductors into engagement with individual ones of said contacts, a relay for controlling the connection of said incoming conductors to contacts with which said outgoing conductors are engaged, a circuit for operating said relay, means for operating said magnet, and contacts on said magnet for completing said circuit only when said magnet is operated.

3. In a telephone system, an automatic switch adapted to hunt for an idle outlet in a group of outlets, means for moving said switch from one outlet to the next outlet, a circuit for testing each outlet to which the switch is moved to determine the idle or busy condition thereof, and contacts in said switch for closing said circuit, said contacts arranged to prevent the closure of said circuit during the movement of said switch from a contact with which it is associated.

4. A telephone system as set forth in claim 3 in which said circuit for testing each outlet includes a rectifier to prevent the operation of said circuit from a potential of one polarity which may be encountered on said outlets.

5. In a telephone system, an automatic switch, a plurality of lines accessible to said switch, a fast relay and a slow relay operated to control the connection of said switch to an idle one of said lines, a control conductor to which guarding potential is at times connected, a holding circuit for said fast relay and said slow relay from guarding potential connected to said control conductor, said fast relay being effective responsive to a momentary disconnection of guarding potential from said control conductor to disable said holding circuit, said slow relay thereafter being effective for controlling the release of said switch and for connecting guarding potential to said control conductor to prevent seizure of said switch while it is releasing.

6. A telephone system as set forth in claim 5

in which said automatic switch is arranged to hunt for an idle line in a group of lines, said fast relay being effective for controlling the hunting operation of said switch and said slow relay being effective for completing the connection between said switch and an idle one of said lines.

7. In a telephone system, an automatic switch, a fast to release relay, a slow to release relay, a control conductor to which guarding potential is at times connected, means for operating said switch, means for releasing said switch, means for operating the relays in case said switch is operated, means for completing a holding circuit for the relays from guarding potential connected to said control conductor, said fast to release relay being effective to release and disable said holding circuit responsive to a momentary removal of guarding potential from said control conductor to thereby assure the release of said slow to release relay, said slow to release relay being effective upon release to operate said means for releasing said switch and to connect a guarding potential to said control conductor thereby guarding said switch during its release operation.

8. In a switching device, a wiper set, a plurality of contact sets, first electro-mechanical means for moving said wiper set over said contact sets, second electro-mechanical means for stopping said wiper set on one of said contact sets, a first circuit for operating said first electro-mechanical

means, a second circuit including a wiper of said wiper set for operating said second electro-mechanical means, contacts on said first electro-mechanical means, and means including said contacts for preventing the simultaneous closure of said first circuit and said second circuit.

9. In an automatic switch, a plurality of stationary contacts, a movable contact for engagement with said stationary contacts, a magnet, means for energizing said magnet to move said movable contact over said stationary contacts, a relay, a circuit including said movable contact for energizing said relay to stop said movable contact on one of said stationary contacts, and means for preventing the simultaneous energization of said magnet and said relay.
